R. GIRARDELLI

STABILIZING DEVICE

Filed May 3, 1920

UNITED STATES PATENT OFFICE.

RICCARDO GIRARDELLI, OF ROME, ITALY.

STABILIZING DEVICE.

Application filed May 3, 1920. Serial No. 378,637.

To all whom it may concern:

Be it known that I, RICCARDO GIRARDELLI, a subject of the King of Italy, residing at Rome, in the Kingdom of Italy, have invented certain new and useful Improvements in Stabilizing Devices, of which the following is a specification.

It is known that a direction may be individuated in space by a zenithal and by an azimuthal angle which are read upon graduated circles, these latter being respectively mounted upon a vertical and upon a horizontal support.

The present invention relates to a device for individuating a direction in space in the case that the supports carrying the graduated circles are movable in respect of the direction to be individuated.

Hereinafter an embodiment of the invention will be described showing the device as applied to order-transmitters for naval guns in order to keep steady the direction of the gun axle notwithstanding the rolling and the pitching of the ship; but it will be understood that whatever be the application of said device to apparatuses intended to individuate and keep steady a direction in space, it will still fall within the scope of the present invention.

In naval guns, the different movements of which are controlled from a distant station by means of well known devices, called order-transmitters, the transmission of the firing data, i. e., of the angles of elevation and direction of the pieces in laying them, is usually effected without taking into consideration the oscillations of the ship, that is to say, the data are furnished from the controlling station assuming that the support of the pieces be steady, and motors acting upon the pieces impart to them the direction and elevation required by causing them to turn about two axis invariably connected with the ship and which under normal conditions, that is when the ship is on an even keel, are supposed to be one horizontal and the other vertical; from which it follows that when the sea is rough and the ship rolls and pitches, the angles formed by the pieces when they are fired, referred to the true vertical and to the horizon, do not correspond to those that the pieces should actually form, since these, owing to the aforesaid movements do not keep in space a determined and constant direction. Hence

the firing under such conditions becomes inaccurate and very difficult. The above said difficulties may be overcome, according with this invention, by inserting on the transmitting line, leading from the transmitting station to the gun, a device comprising:

(a)—A reference plane, for instance the rotation plane of a gyroscope cardanically suspended and having such a degree of liberty as to keep its rotation axis in a constant vertical direction irrespective of the movements of the movable support connecting the gyroscope with the ship.

(b)—A movable pointer which, with reference to the invariable plane of rotation of the gyroscope, may be given an inclination and a direction corresponding to those which are to be assumed and maintained by the piece axle.

(c)—Electrical means for ascertaining and continuously transmitting to the gun rotations equal and contrary to those the pointer set, trimmed with respect to the invariable plane of the gyroscope, performs, owing to the rolling and pitching of the ship, with respect to a plane connected with the ship and parallel to that with reference to which have been given to the gun the elevation and direction indicated by the order transmitting station.

It is clear that in this way the gun, by always performing rotations equal and contrary to those of the ship, maintains in the same manner as the pointer connected with the gyroscope a determined and constant direction, and firing may take place with the guns accurately set in the same way as if the ship were at rest on a perfect even keel.

In the annexed drawing in which the arrangement of a device according with this invention is shown schematically by way of example:

Fig. 1 shows a diametral vertical section, and

Fig. 2 a horizontal section of the apparatus, the transmitting device proper, which may be of any approved type having been omitted for clearness sake;

Figs. 3, 4, 5, 6 relate to particulars.

In Fig. 1, —1— indicates a gyroscope rotating about the axis 2; said gyroscope being suspended within a frame 30 and this latter being cardanically suspended within frames 11 and 11.

The frame 11 is mounted rotatably on 110

collars C and C₁ which rotate upon supports, not shown in Fig. 1, fixed to the ship body.

The frame 30, the axle 2 of which is constantly vertical owing to the gyroscope rotation, carries two pivots 3 and 3₁ and about these latter a frame or ring 3₁₁ oscillates which is constantly maintained in the gyroscope rotation plane.

10 —4— and —5— are two small metal rods fastened at the two opposite ends of a diameter of ring 3₁₁ and slightly touching with their free ends two spherical caps 6 and 7 supported by stirrups 8 and 9 the first of 15 which swings around the horizontal pivots 10 fastened to the frame 11 and the second around the vertical axis O₁ O₂; said caps forming as a whole, as shown in Fig. 1, approximately a spherical recess within 20 which is mounted the gyroscope.

The caps, made of insulating material, have their inner side lined with metallic contact surfaces 12, 13, 14, 15, respectively interrupted by two grooves 16 and 17 filled 25 with insulating materials, the first horizontal and the second vertical.

Under normal conditions, that is to say when the ship is on an even keel, the axis of pivot 2 coincides with the axis O₁ O₂ of 30 frame 11, rod 4 corresponds to groove 16 and rod 5 corresponds to groove 17; further groove 16 lies in the plane of rods 4 and 5 and of ring 3₁₁ the pivots of said ring being kept horizontal by the gyroscope, and groove 35 17 lies in the plane of axle 2 and of rods 4 and 5.

The cap 6 which rotates about the horizontal pivots 10; is balanced by means of 40 counterweights 18 which make easy its turning movement, and to the upper edge of cap 6 is fastened a toothed segment 20 meshing with a wheel 23 keyed to a shaft 33.

The shaft 33 passes through the collar C and carries a small arm 40 on which are 45 loosely mounted the two bevel gears D revolving between the bevelled rims of a wheel —A— loose on collar C and of a wheel B loose on shaft 33. The wheel A has also a toothed peripheral rim in mesh with a wheel 50 41 mounted on the shaft 42 of an electric motor M₁. To shaft 42 is also keyed a gear wheel 43 in mesh with a pinion 44 hereafter referred to.

To the collar C is keyed a gear wheel 34 in 55 mesh with a wheel 45 keyed to the shaft 46, to which is also keyed a gear wheel 47 in mesh with the toothed peripheral rim of the wheel B.

It will be seen that when the collar C, 60 and consequently the small shaft 46, the wheels 45, 47, B, are kept motionless, upon the operation of the motor M₁ the wheel A turns and then gear D rotates between wheel A and the stationary wheel B thus 65 causing the shaft 33 to rotate and conse-

quently the cap 6 to swing about its pivots 10.

Now the motor M₁ is without current as long as the small rod 4 is situated in front of the groove 16. It will however turn in one or the other direction according to whether by means of the small rod 4 the current through the switch S₁ is sent from the one or the other of the metallic surfaces 70 12, 13 to which are attached the two conducting wires 24 and 25 connected also with said switch S₁. The switch is so arranged that the direction of rotation of the motor M₁ is such as to cause the cap 6 to swing in the direction required to bring 75 the groove 16 again in the same plane as the small rod 4.

Similarly, the two metallic surfaces 14 and 15 of cap 7, by means of the two wires 80 26 and 27 terminating at switch S₂ are connected to a second electrical motor M₂.

Motor M₂ transmits its movement to the shaft 63 which carries the stirrup 9 which at its top has an eyelet to be able to freely swing about the collar C, a gear wheel 48 being keyed to the shaft 49 of motor M₂ and said wheel meshing with a pinion 50 and with the peripheral toothed rim of the wheel A₁ of a differential A₁ B₁ D₁ similar 95 to the differential A B D. Moreover, upon the differential A₁ B₁ D₁ acts another motor M₃, to the shaft 51 of which are keyed the two gear wheels 52 and 36; wheel 52 meshing with the toothed peripheral rim of the wheel B₁ loose on shaft 63, and wheel 36 100 meshing with the wheel 35 keyed to the collar C₁.

It will be seen that when motor M₃, and consequently collar C₁ and wheel B₁, are 105 kept motionless, upon the operation of the motor M₂ the wheel A₁ turns and then gear D₁ rotates between wheel A₁ and the stationary wheel B₁ and with its arm fastened on the shaft 63 causes the latter and the stirrup 9 to rotate too.

Now motor M₂ is without current as long as the small rod 5 is situated in front of the groove 17 but it will turn in one direction or the other according to whether by means of the small rod 5 the current through the switch S₂ is sent to it from the one or from the other of the metallic surfaces 110 14—15 at which terminates the two wires 26, 27.

The switch S₂ is so arranged that the direction of the motor rotation is such as to cause the cap 9 to rotate in the direction required to bring the groove 17 again in front of the point of the small rod 5. If, 115 on the contrary, the motor M₂ and consequently also the wheel A₁ are motionless, the following two effects will be produced upon the motor M₃ being turned:

The wheel 52 causes the wheel B₁ to rotate and the latter, causing in its turn the 120 125 130

gears D_1 to revolve upon the stationary wheel A_1 imparts rotation to the shaft and consequently to the stirrup 9.

On the other hand, the wheel 36 by causing the rotation of the wheel 35, keyed to the collar C_1 imparts the rotary movement to the frame 11 and consequently to the whole suspension of the gyroscope so that also the small rod 5 will turn around the axis $O_1 O_2$ maintaining said rod always in front of the groove 17.

However, should the shaft 33 connected with the motor M_1 remain motionless during this rotation, this would cause a rotation of the sector 20 and consequently an undesired oscillation of cap 6 which latter must be operated only by motor M_1 . Said undesired oscillation of the sector 20 is prevented by the shaft 46 and the wheels 45-47. In fact, the motor M_1 being motionless, and the wheel A being consequently stationary, upon a rotation of the frame 11 together with the collar C, which forms a portion of the latter, a rotation is imparted to wheel 34 and, through shaft 46, a movement equal to that of wheel 34 is transmitted to the wheel B, which causes the pinion D to revolve upon the motionless wheel A so that also shaft 33 turns in such a way as to prevent the arc 20 from rotating.

With this premise, be it assumed for simplicity's sake that the ship be on an even keel, and that the gun to be controlled be arranged with the horizontal axis in the vertical of its position of rest.

Under such conditions the frame 3₁₁ is disposed horizontally and accordingly also the two small rods 4 and 5, the first one in front of the groove 16 which lies in a horizontal plane too, and the second one in front of the groove 17 which lies in a vertical plane passing through the axis $O_1 O_2$. In that case, the shaft 2 of the gyroscope is vertical and its axis is in alignment with the axis of the two shafts 33-63.

The axis $O_1 O_2$, belonging in common to these three shafts, is parallel to the vertical axis of the range officer's telescope and it is to be remarked that, whatever may be the movement of the ship, the axis $O_1 O_2$ which is integral with the latter, remains always parallel to that of the telescope, so that the angle of direction transmitted by the telescope is always exactly measured in respect of the axis $O_1 O_2$. The small rods 4, 5 are parallel to the axis of the gun and, in the aforesaid position of rest, to the optical axis of the horizontally disposed telescope. When the gyroscope is now set in motion, its rotation plane owing to its being horizontal maintains itself in this position, irrespective of the oscillation of the ship.

Be it now supposed that it is necessary to give the gun a certain inclination. The firing master transmits the said angle by

means of the motor M_4 suspended below within the frame 30 of the gyroscope. The motor M_4 causes the frame 3₁₁ to rotate and the small rod 5 is lowered sliding always along the groove 17 whilst the small rod 4 is raised, leaving the groove 16 and coming into contact with the metallic surface 12. Thus the circuit of the motor M_1 is closed through the wire 24 and the motor starts acting upon the differential A B D, in the way described hereinbefore, in order to lift the cap 6 causing the latter to swing about the pivots 10 as far as to bring the groove 16 again in front of the small rod 4.

It will be seen that the cap thus swings about the same angle about which the small rod 4 has moved, that is about the elevation angle of the gun, whereupon the motor is stopped. During its operation the motor M_1 , by means of the wheel 43, drives also the wheel 44 mounted upon the shaft of an order transmitter 54 which thus transmits to the gun the angle of elevation assigned to it by the firing master.

Be it now assumed that the ship starts rolling and for greater simplicity's sake be it supposed that the movement takes place in the vertical plane passing through the axis $O_1 O_2$ and the groove 17 in other words that the gun be directed in a vertical plane perpendicular to the middle plane of the ship. During this movement the small rod 5 remains inoperative and the motor M_2 remains motionless. The small rod 4, on the contrary, leaving the groove 16 comes into contact with the one or with the other of the surfaces 12 and 13 and the motor M_1 turns in one direction or in the other to bring, by means of the differential A B D the groove 16 again in front of the small rod 4 and by means of the wheel 44 causes the gun to rotate, in elevation, about an angle equal and contrary to that by which the ship has heeled, so as to keep fixed in space the direction of the gun.

Supposing now again that the ship be on an even keel and that the gun, with any elevation whatever, shall be caused to swing about a certain angle of direction. The firing master transmits this angle by the aid of the motor M_3 which by acting upon the differential A₁ B₁ D₁, in the manner described hereinbefore, while the motor M_2 and consequently the wheel A₁ are motionless, by means of the wheel 35 causes the frame 11 to swing with the gyroscope suspended to it, and by means of the satellite pinion D₁ causes to rotate shaft 63 carrying the stirrup 9.

In this way the small rod 5 and the groove 17 turn and are kept the one in front of the other, so that motor M_2 remains inoperative. The gun is connected with a motor (not shown in the drawing) similar to the motor M_3 and serving to rotate the gun in

direction by the same angle by which rotates the frame 11.

Since the vertical axis of the telescope is parallel to the axis $O_1 O_2$ whatever may be the inclination of the ship, it ensues that if the telescope is kept directed upon the target also the orientation of the frame 11 is kept correct.

Be it now supposed that the ship is rolling and pitching and that during these movements the small rod 5 leaves the groove 17 coming into contact with one of the metallic surfaces 14, 15. Then motor M_2 will start turning and, as the wheel B_1 is motionless, by means of the differential $A_1 B_1 D_1$ it will cause to rotate the shaft 63 and consequently swing the stirrup 9 as far as to bring the groove 17 again in front of the small rod 5. On the other hand, by means of the wheel 50, it causes to rotate the shaft of an order transmitter 55 which transmits to the gun a movement in direction equal and contrary to that which it would perform through the action of the ship oscillation.

The movements of the two small rods have up till now been considered separately as being independent the one from the other. In practice the same oscillation may give rise to both of said movements. In this case as soon as the ship starts oscillating the small rods by leaving the grooves come into contact with the metallic surfaces of the caps 6 and 7 thus closing the circuits of the two motors and these are driven in the direction required so that the rotary movement imparted by them to the caps be such as to bring the grooves again in front of the small rods and to interrupt the circuits, the caps thus effecting each simultaneously to the other an angular movement equal and contrary to that effected by the ship, so that the gun always keeps in space the constant position necessary for firing.

The small rods carried by the gyroscope and the metal caps with the insulating groove, together with the motors, work substantially as one of those devices used for the method of distant control termed "follow-up-system," in which a movable piece, as the caps in the present instance, by being driven by a motor, revolves until it comes against a pointer which is also movable. In the present case the two small rods 4 and 5 are kept in an invariable position by the gyroscope through the simple effect of the contact of the pointer on either side, without requiring the least mechanical effort, which is performed, by the motor.

In order to afford a complete understanding of the construction and operation of the apparatus, the following explanation may be added:

The ring 3'' extends over the ring 11', in the direction 4—5, and is shaped as shown in Figs. 3 and 4; the recesses 3''' allow the

ring 3'' to swing with respect to the ring 11' about a predetermined angle.

The ring 3'' is electrically insulated with respect to the pivots 3 and 3' and with respect to the members transmitting to it the movement of the motor M_4 . A flexible wire 65 (Fig. 2) constantly connects the ring 3'' with the pole + of an electric power source not shown in the drawing, the pole — of that source being connected to the switch S_1 through the wire 66 and to the switch S_2 through the wire 67 (Fig. 1).

As shown in Figs. 3, 4, the motor M_4 transmits the movement to the ring 3'' by means of the pinion 68 keyed on the motor shaft and meshing with the wheel 69, a crank 70 being connected by the articulations 70' and 70'' to the ring 3'' and to the wheel 69.

The main azimuthal movement of the device as a whole, and consequently of the rods 4—5, is produced by the motor M_3 , but the contact 5 serves to impart to the device correcting movements for stabilizing any element in azimuth when the rotor of the gyro tends to spin in azimuth.

In Figs. 5 and 6, *a*, *b* and *c*, *d* are respectively plan views of the cap 7, and the metallic surfaces 14 and 15; *b*, *c* is the interrupting groove 17; and 71 is the point where the rod 5 contacts with the cap. It will be seen that, when the ship is on an even keel, the vertical axis $O_1—O_2$ (connected to the ship), the axis 2 (constantly kept vertical by the gyro) and the middle line *m*, *n* of groove 17 lie in a common vertical plane; in said conditions the axis of rotation 3—3' of ring 3'' is perpendicular to said plane, and the contact line, upon which may oscillate the point of rod 5, coincides with *m*, *n*.

Assuming now that the ship oscillates in such a way as to cause the axis $O_1—O_2$ and consequently the groove *b* *c* to form the angle α with the contact line (constantly kept vertical by the gyro) it will be seen that the point of rod 5 will run upon the surfaces 14 or 15 along the contact line *m*, *n*, the contact point resulting, for instance, displaced from 71 to 71'. During the displacement of the contact point upon the surface 15 the current is sent to the switch S_2 by the wire 27 and the motor M_2 rotates in the direction proper for interrupting the contact of rod 5 with the surface 15, that is to say, the motor M_2 rotates, until the insulating groove comes in front of the contact point 71'. It is obvious that during said movement the points of the groove will perform circular arcs like 71'—71'' perpendicular to the axis of rotation $O_1—O_2$, and upon the movement being stopped, the point 71'' will be lifted in space of a quantity $y—71''$; it ensues that the line joining the Cardan centre with the central points of grooves 16—17 follows the movement of the ship, but is automatically brought to coincide with the line joining the

Cardan centre with the contacts 4 and 5 (which line with regard to the zenithal movements is independent from the movements of the ship) and $71'' - y$ is in azimuth 5 the correcting movement required owing to the zenithal movement $71 - 71'$ and the inclination α of the ship.

I claim as my invention:

1. In combination with an unstable support, a device mounted thereon for individualizing and keeping fixed in space a direction determined by any two angles irrespective of the movements of the said unstable support, the said device comprising a rotatable 10 suspension frame mounted on the said unstable support, a frame cardanically suspended in the said suspension frame, a gyroscope mounted and cardanically suspended in the said second frame, the axes of 15 rotation of the said gyroscope and the said suspension frame being coincident and vertical when the said unstable support is in its position of rest, a third frame rotatably mounted in the said gyroscope frame and 20 adapted to rotate about a diameter of the gyroscope ring, two diametrically opposite contact rods provided on the said third frame, a first spherical cap rotatable about 25 said third frame and having a metallic surface with an insulated groove provided 30 therein in a horizontal diametral plane comprising the axis of rotation of the said third frame, a second spherical cap rotatable about 35 the said gyroscope and having a metallic surface and an insulated groove provided 40 therein in a vertical diametral plane comprising the axis of rotation of the said gyroscope, means for rotating the said suspension frame to thereby bring the vertical plane containing the said two contact rods

into any desired orientation, means allowing the said third frame to swing about the horizontal rotation diameter to thereby give the line of the said contact rods any desired inclination upon the horizon, means causing 45 the rotation of the said first and second spherical caps to thereby bring their insulated grooves again into register with the corresponding rods upon each motion of the said movable support, so that the axis of the 50 suspension frame is no longer vertical and does no longer fall in alignment with the axis of rotation of the said gyroscope.

2. The combination with a gyroscope and a frame therefor, of a frame and two contact rods mounted rotatably around a diameter of the said gyroscope frame, a movable circle mounted rotatably around the rotation axis of the said gyroscope and carrying in its rotation the frame with the contact rods, 55 a movable circle mounted rotatably around one of its diameters coinciding with one diameter of the gyroscope ring, caps with internal metallic surfaces provided with insulated grooves connected with the said 60 movable circles, electric motors and gears driven by them arranged to rotate the movable circles; the said contact rods, the said metallic caps with the insulated grooves, the said electric motors and the said interposed 65 gears being arranged to act as an electrical follow-up-system keeping the said rods always in correspondence with the grooves.

In testimony whereof I have affixed my signature in the presence of two witnesses, 70 this 8th day of April, 1920.

RICCARDO GIRARDELLI.
